US0D1063947S

(12) **United States Design Patent** (10) **Patent No.:** **US D1,063,947 S**
(45) **Date of Patent:** **** Feb. 25, 2025**

(54) **ELECTRONICS HOLDER**

(71) Applicant: **Dongguan Kaishuo Electronics Technology Co., Ltd.**, Dongguan (CN)

(72) Inventor: **Jing Cai**, Dongguan (CN)

(73) Assignee: **Dongguan Kaishuo Electronics Technology Co., Ltd.**, Dongguan (CN)

(**) Term: **15 Years**

(21) Appl. No.: **29/944,707**

(22) Filed: **May 29, 2024**

(51) LOC (15) Cl. **14-02**

(52) U.S. Cl.

USPC **D14/447**

(58) **Field of Classification Search**

USPC D14/253, 452, 447; D13/108; D3/218

CPC H04M 1/04; H04M 1/06; H04M 1/08; H04M 1/10

(57) **CLAIM**

The ornamental design for an electronics holder as shown and described.

DESCRIPTION

FIG. 1 is a front and top perspective view showing of an electronics holder showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is perspective view showing the electronics holder in the alternate configuration.

The broken lines in the figures illustrate portions of the electronics holder that form no part of the claimed design.

1 Claim, 9 Drawing Sheets
